(57) CLAIM

The ornamental design for a ring for placement between a hairbrush handle and head, as shown and described.

DESCRIPTION

FIG. 1 is a rear perspective view of a ring for placement between a hairbrush handle and head showing my new design in its environment;

FIG. 2 is a front perspective view of the ring of FIG. 1;
FIG. 3 is an enlarged front elevational view of FIG. 2;
FIG. 4 is a bottom plan view of FIG. 3, the top plan being a mirror image;

FIG. 5 is a rear elevational view of FIG. 3;

FIG. 6 is a side elevational view of FIG. 3, the opposite side being a mirror image;

FIG. 7 is a rear perspective view of a second embodiment of the design of FIG. 1, shown in its environment;

FIG. 8 is a front perspective view of the ring of FIG. 7;
FIG. 9 is an enlarged front elevational view of FIG. 8;

FIG. 10 is a bottom plan view of FIG. 9, the top plan being a mirror image;

FIG. 11 is a rear elevational view of FIG. 9; and,

FIG. 12 is a side elevational view of FIG. 9, the opposite side being a mirror image.

The broken lines showing of a portion of a hair brush and a handle in FIGS. 1, as well as broken lines showing of a portion of a hair brush and a handle in FIGS. 7 are for illustration purposes only and forms no part of the claimed design.
